[57] CLAIM

The ornamental design for a bulb and battery storage panel, as shown and described.

DESCRIPTION

FIG. 1 is a front elevational view of a bulb and battery storage panel showing my new design;

FIG. 2 is a rear elevational view thereof;

FIG. 3 is a right side elevational view thereof, the left side being a mirror image of that shown;

FIG. 4 is a top plan view thereof, the bottom being a mirror image of that shown;

FIG. 5 is a horizontal cross-sectional view thereof, taken along line 5—5 of FIG. 1; and

FIG. 6 is a vertical cross-sectional view thereof, taken along line 6—6 of FIG. 1.

Fig. 3. Fig. 6.
Fig. 2.

Fig. 1.
Fig. 6.

Fig. 5.

Fig. 4.
